UNITED STATES PATENT OFFICE.

HENRY E. PRIDMORE, OF SPRINGFIELD, OHIO.

GRAIN-BINDER.

SPECIFICATION forming part of Letters Patent No. 234,806, dated November 23, 1880.

Application filed January 23, 1880.

To all whom it may concern:

Be it known that I, HENRY E. PRIDMORE, of Springfield, in the county of Clarke and State of Ohio, have invented an Improvement 5 in Grain-Binders, of which the following is a specification.

My invention relates to grain-binding machines, but more particularly to the mechanism by which the gavel is bound and the knot 10 tied; and it consists in the construction, arrangement, and operation of certain mechanism, which is fully and clearly set forth in the specification, and referred to in the appended claims.

15 In the drawings, Figure 1 is a perspective view of my improved knot-tying mechanism, looking up from beneath the machine. Fig. 2 is a plan of same, looking up from beneath.

Fig. 3 is a front elevation of same. Figs. 4, 5, 20 and 15 are detached views of the cord-holder, knife, and tying-hook. Fig. 6 is a perspective view of the tying mechanism proper. Fig. 7 is a section of same. Fig. 8 is a plan of same. Figs. 9 to 14 are views of the cord during the 25 progress of tying the knot.

A is a binding-frame, which rotates upon a vertical axis within the bearing A'. Upon its outer end, and free to slide thereon, is an oblique sliding plate, B, which is provided with 30 a rack, C, slot D, and a cam-projection, E.

Motion is imparted to the slide B by means 35 of the lever F' and connecting-bars F and F², the bar F being in its turn operated by the cam-plate G, to which it is connected by the pin f. This cam-plate G is pivoted to the frame A at G'. It is provided with a cam-slot, g, and a small pivoted cam, h², which is pressed against a pin or projection by a spring, and which operates the knife to sever the cord.

40 Working in the cam-slot g is a roller or pin, h, which is attached to the end of a bar, H, guided by a link, h'. This bar H operates the knife to sever the cord when it is drawn back by the roller or pin h striking the cam h², as 45 hereinafter set forth.

The cord-holder I is pivoted at I' obliquely to the frame A, and is provided with a pin or roller, i, which works in the slot D, and thereby governs the motions and time of movements 50 of said holder. There is also a pin, i', which

is thrown up or allowed to be depressed by the cam-piece E, and insures the movement of the holder, so that it shall be thrown to or from the tying mechanism proper at the required instant. The holder, when thrown out, rests 55 against a pin, a, on the frame A.

The jaw J, carrying the knife, slides in a box, J', secured to the holder I, and is connected to the bar H by the pin j². The end of the jaw is provided with two teeth, j and j', which work 60 between two teeth, k k', on the holder I, as shown in Fig. 5. When the teeth j and k pass each other the cord is severed.

Secured to one side of the holder I is a spring-finger, L, the end of which is between the teeth 65 j' and k'. The cord is held between the tooth k' and finger L, the springing action of the latter insuring a firm hold.

Upon the holder I is secured a tying-hook, M, which can be set forward or back with reference to said holder by means of a screw, m, which, when tightened, presses it forward, and when loosened allows the resilience of the bent 70 rear arm to draw it back.

The knot-tyer proper, N, is secured to the 75 frame A by the foot n, which passes through the slot b in the sliding plate B. The casing N', open on one side, is secured to or forms part of foot n. A pinion, O, is held within said casing by a shoulder, the outer face of 80 said pinion being formed into an incline plane, o, and terminating in a hook, P. Within the casing N' and pinion O is another piece, Q, which is secured to the casing and has an opening, q, all the way through it. At the 85 outer end, and on one side of the opening, is a projection, S, and on the other side is piece R, attached to a spring, r, which is secured to the piece Q at the inner end, as shown in Fig. 7. The hook M, attached to and operated by 90 the holder I, is thrust through between the projection S and piece R when the loop is being made, and when withdrawn it carries the ends of the cord with it through the loop, tightening the knot by the springing action of 95 the spring r and piece R. The pinion O meshes with the rack C, and as said rack is reciprocated the looper composed of the pinion, with its inclined plane and hook, is rotated first in one direction and then in the other.

Secured to the casing N' is a shield, n' , which covers the rack and prevents the cord being caught therein.

The knotter and its appendages are set in an oblique position with reference to the grain table or platform for the purpose of properly presenting the binding-cord to said knotter, that in its revolution it shall catch and loop the cord in such a manner that the cords shall remain distinct and the loop easily operated upon.

Secured to the frame A is a curved finger, T , which partly encircles the looper, the end resting on the inclined plane until the hook P reaches it, when it is pressed out, thereby allowing the loop which had been previously kept between the finger and incline plane to pass to the other side of the finger prior to the final action in tying the knot.

20 The hook P is so constructed that the opening forming the hook is parallel to the axis of rotation of the looper, or to the axis about which said hook rotates. This is clearly shown in Figs. 6, 7, and 8.

25 The guide U , secured to plate A , insures the proper presentation of the cord to the knot-tyer. A platform, V , is secured to the frame A and rotates with it. Situated over the platform is the binder-arm W , which presents the cord to the knot-tying mechanism. It is secured to the end of a rocking shaft, W' , which rocks in bearings $X X$. The cam-plate G is oscillated by any suitable means.

The operation is as follows: The cord being placed in the holder and passed around the gavel, as shown in Fig. 1, the binder-arm W descends and presents the cord to the holder. The cord is then as shown in Fig. 9. The cam-plate G is then oscillated, which action draws 40 the teeth $j j'$ in and holds the cord firmly. It also throws out the plate B and rack C , which rotates the looper, the hook P catching the cords and carrying them around to form the loop. The roller i , following the cam-slot D , 45 causes the holder I to be projected toward the looper, giving cord wherewith to make the knot. As soon as the looper has made one revolution the cord is in the form of a loop, as shown in Fig. 10, the hook P being at the 50 point y . As the looper continues its revolution the loop is ready to slip from under the finger T , as shown in Fig. 11, in which y indicates the position of the hook P . As it continues to rotate the pin h passes the cam h^2 , 55 pressing it up. The plate B moves the end of the cam-slot D to the roller i , projecting it and the entire holder toward the looper. At the same time the loop is freed from the finger T as the twister rotates, and the cord assumes 60 the position shown in Figs. 6 and 12, in which last figure y shows the position of the hook P . During the movement of the holder I toward the looper the hook M is projected to its greatest extent through the piece Q , and presents the 65 hook to the part of the cord next to the holder, as shown in Fig. 6. The cam-plate G is then

oscillated in the opposite direction. When the pin h strikes the cam h^2 it is drawn back, which action draws the knife-tooth j farther into the holder and severs the cord. The looper is now 70 rotating in an opposite direction, which frees the loop from the hook P , and at the same time the holder recedes, carrying with it the hook M , which, in turn, carries the ends of the cord through the loop, as shown in Fig. 13. 75 The cam-plate G still moving, the holder is thrown back and the jaws opened for the reception of fresh cord from around a new gavel, and at the same time the hook M carries the ends of the cord down between the projection 80 S and the spring-head R , which tightens the knot, as shown in Fig. 14. The binder-arm is then raised and the bundle discharged from the platform.

Having now described my invention, what I 85 claim, and desire to secure by Letters Patent, is—

1. A looping-head, N , in combination with a cord-holder, I , a tying-hook, M , carried by said holder, and devices by which the holder 90 is operated in such a manner that sufficient cord is delivered to make the knot without taking any from the bundle, substantially as and for the purpose specified.

2. The combination of the looper-pinion O , 95 carrying the hook P , with the piece Q , projection S , spring r , spring-head R , and hook M , substantially as and for the purpose specified.

3. In a knot-tyer, the looper-hook P , provided with an opening parallel to the axis of 100 rotation, in combination with the hook M , attached to and operated by the holder, substantially as and for the purpose specified.

4. In a knot-tyer, the combination of projection S , spring-head R , spring r , and hook 105 M , attached to and operated by oscillating frame I , substantially as and for the purpose specified.

5. In a knot-tyer, a looper provided with an inclined plane along its outer face and a hook, 110 P , in combination with a curved finger, T , substantially as and for the purpose specified.

6. The hook P of a looper in which the opening forming the jaw is parallel to the axis of rotation of the looper for the purpose of 115 catching the cord, substantially as described.

7. The combination of frame A , sliding plate B , provided with a rack, C , and cam-slot D , knot-tyer N , and cord-holder, with intermediate operating devices, substantially as and 120 for the purpose specified.

8. The combination of the obliquely-pivoted oscillating cord-holder I , provided with roller i , reciprocating slide-plate B , provided with rack C and slot D , looper N , binder-frame A , 125 and gaveling-platform V , which rotates about a fixed axis at A' , the looper, holder, and plate being arranged and operated in plane oblique to the gaveling-platform, all constructed and operated substantially as and for 130 the purpose specified.

9. A cord-holder which oscillates upon a

fixed bearing and carries a knife to sever the cord, and a hook to form the knot, substantially as and for the purpose specified.

10. In a cord-holder, the combination of the teeth $j j' k k'$ and the spring-finger L, substantially as and for the purpose specified.

11. The combination of the frame A, cam-plate G, bars F² and F, lever F', and a slide-plate, B, substantially as and for the purpose specified.

12. The combination of the cam-plate G, provided with a slot, g, and pivoted cam h^2 , bar H, pin h, holder I, and clamping-jaw J, substantially as and for the purpose specified.

13. In a grain-binder, the combination of guide U, looper N, hook P, provided with an opening parallel to the axis of rotation, and

oscillating holder I, which is operated to move to and from the looper with positive motion, substantially as and for the purpose specified. 20

14. The looper-pinion O, provided with an incline plane, o, and a hook, P, the opening in which is parallel to the axis about which it rotates, in combination with a reciprocating rack, C, and hook M, attached to and operated by an oscillating holder, I, substantially as and for the purpose specified. 25

In testimony of which invention I hereunto set my hand.

HENRY E. PRIDMORE.
